UNITED STATES PATENT OFFICE.

HENRY K. B. DAVIS, JR., OF PROVIDENCE, RHODE ISLAND, ASSIGNOR TO THE SWING-RITE CO. INC., OF PROVIDENCE, RHODE ISLAND, A CORPORATION OF RHODE ISLAND.

SAWING MACHINE.

Application filed March 2, 1922. Serial No. 540,578.

To all whom it may concern:

Be it known that I, HENRY K. B. DAVIS, Jr., a citizen of the United States, residing at Providence, in the county of Providence and State of Rhode Island, have invented

5 certain new and useful Improvements in Sawing Machines, of which the following is a specification.

This invention relates to improvements in

10 the construction of sawing or wood-cutting machines more particularly adapted for operating upon material in strip form, and the object of this invention is to provide a pair of saws or other cutters having their working faces set vertically inclined in opposite directions to operate on opposite sides or edges of the work and to cut the work preferably with beveled sides as it is passed through the machine.

15 A further object of the invention is to provide means whereby the work support may be vertically adjusted in its carriage relative to the saws or cutters so that the depth of cut may be regulated, and also to

20 provide adjustable means for the work-support whereby one end may be raised relative to the other to obtain an end-to-end taper on the work and to regulate the extent of such taper.

25 A still further object of the invention is the provision of a work-support having elevations or depressions in its work-supporting surface and cooperating means for bending the work to follow the contour of the

30 support whereby when the different strips are cut by the saws or cutters the finished product will have the contour or shape desired.

With these and other objects in view, the invention consists of certain novel features

35 of construction, as will be more fully described, and particularly pointed out in the appended claims.

In the accompanying drawings:

Figure 1 is a side elevation of my improved sawing machine and showing a portion broken away to better illustrate the intermittent driving mechanism for the work-carriage.

Figure 2 is a plan view of the machine.

50 Figure 3 is a front elevation of my improved machine.

Figure 4 is a side elevation partly in section showing the carriage with the work-support adjustably mounted therein.

Figure 5 is a perspective view showing 55 an end portion of the carriage.

Figure 6 is a perspective view showing an end portion of the work-support detached from the carriage.

Figure 7 is a side elevation of the work-support which is provided with raised and depressed portions along its work-supporting surface whereby a thin neck portion of undulating shape may be formed in the work when cut by the saws.

Figure 8 is an end elevation at the section line 8—8 in Figure 4 showing the carriage as mounted in its dovetailed ways and the screw adjustment for raising the work-support in the carriage.

Figure 9 is an end elevation showing a section of the work-support with the work mounted thereon and showing the presser-foot as supporting the work while being cut by the saw on the opposite side.

Figure 10 is the same as Figure 9 showing the presser-foot and the roller-guide for holding the work onto its support and assisting in supporting it while being cut by the saw on the opposite side.

Figure 11 shows the work on its support after having been acted upon by both of the saws.

Figure 12 is a side elevation of the work guide supporting frame mounted above the 85 work and adjacent the operating position of the two saws and showing the guides for supporting the work while being acted upon by the saws.

Figure 13 is a bottom edge view of the 90 guide frame inverted with its various work-guiding members.

Figure 14 shows a finished strip of material cut into V-shape in cross section and tapered gradually from end to end.

Figure 15 shows a strip of finished material as V-shape in cross section varying in its size and taper, being smaller at a point intermediate its ends due to the acting of the saws upon the stock while in a bent or distorted position.

Figure 16 is a perspective view showing the end portion of a sectional shaft built up of a series of V-shaped strips cut on my improved sawing machine.

Figure 17 is a detail showing a dash-pot for cushioning the carriage at the outer end of its stroke.

Figure 18 shows a modified form of a single cutter having a beveled face.

Figure 19 shows a pair of the cutters shown in Figure 18 assembled to provide a disc having a V-shaped cutting groove.

It is found in practice desirable to provide sectional shafts for various purposes such for instance those used in the construction of golf clubs, base ball bats, and other purposes in order to nicely control their weight and flexibility, and it is particularly desirous in the construction of shafts for golf clubs to form them of a tough, fibrous material such for instance as bamboo and the like which is very light in weight and of the desired flexibility, rigidity and toughness, and in order to properly prepare the bamboo stalk I first split it into strips and then saw the strips into substantially V-shape in cross section and subsequently build up or form the completed shaft of a plurality of these sections. My present invention, however, refers to a sawing machine for preparing these strips and the following is a detailed description of one construction of such machine by which the strips may be cut into the desired shape to be assembled.

With reference to the drawings 20 designates the bed of my improved sawing machine, which is provided with dovetailed guides 21 in which the carriage member 22 slides. This carriage member is provided with a narrow, upstanding, central rib 23 which is longitudinally grooved as at 24 for the reception of the work support 25, and at the opposite ends of the carriage this rib is cut away as at 26 and a screw-threaded adjustment stud 27 is threaded into these cut-away portions of the carriage, the upper end 28 of the screw engaging the under side of the work-support and an adjusting wheel 29 is mounted on the stud, the same being graduated on its edge to cooperate with a pointer 30 whereby a micrometer reading of the adjustment of the support may be obtained. This screw member is mounted at either end of this carriage thereby permitting the same to be adjusted vertically bodily to determine the depth of the saw cuts into the work or one end of the support may be raised relative to the other to determine the end-to-end taper of the cuts by the saws.

55 The saws 31, as best illustrated in Figures 2 and 3, are preferably mounted upon the ends of their respective shafts 32 driven by electric motors 33 and these motors are mounted upon their inclined supports 34 and are adapted to be adjusted vertically or angularly by regulating the number or thickness of spacers 35, see Figure 3, that may be positioned between their bases 36 and their supports 34, the motors being retained in adjusted position by bolts 37, the

saws being arranged to overlap each other and the axes of the different motors set one in advance of the other so that the work will be cut first on one side and then on the other as it passes through the machine.

In order to drive this carriage with the desired speed forward to present the work to the saws, I have provided a rack 38 on the bottom of the carriage and I have mounted a mutilated gear 39 on the shaft 40 in the base member which is adapted to be driven by the worm 41 and worm wheel 42, and I have connected a weight 43 by a cord 44 at 45 to the under side of the carriage 22 80 whereby when the gear 39 has made a revolution to move the carriage with its work through the machine it then presents its blank space 46 to the rack which then under action of the weight 43, permits the carriage 85 to return quickly to its starting position, the finished work is now replaced by fresh work by which time the teeth of the gear beyond the space again engages the rack repeating the advancing operation of the carriage to 90 present this fresh work to be operated upon by the saws.

To facilitate setting of the work upon its support I have provided a fixed table 47 supported by brackets 48 from the base of the machine in position to carry a number of unfinished strips on one side, while the opposite side of the table is provided with guide fingers 49 set upright on the table to facilitate the rapid and accurate positioning of the work on its support. To assist in holding the outer end of the work I have provided a spur member 50 located on the end of the work-support see Figure 4, which is inserted into this end of the work 105 to hold it down upon its support and also serves as a stop for this end of the work to prevent it from moving back while being operated upon by the saws. The supporting edge of this supporting member 50 is preferably grooved as at 51 providing a pair of spaced apart, sharp, bearing edges 53 on which the work 52 rests.

It is found in practice that owing to the varying curvature in cross section, of the 115 outer surface of the bamboo strips, a firmer and more secure support is provided by supporting the work on two spaced-apart edges running lengthways of the work, as illustrated in Figures 8 to 11 inclusive.

The work is first positioned on its support with its outer curved surface resting upon the edges 53 of the support, its outer end being secured to the support by a spur 50. The work by means of its carriage is 125 now advanced beneath the guide roll 54 which is mounted between a pair of arms 55 pivoted at 56 on the frame 57 and is under tension of spring 63, which roll serves to press the work down firmly onto its sup- 130

port. The work is next engaged by the presser-foot 58 which is hinged at 59 and is pressed inwardly by spring 60 being limited in its inward swing by a set screw 61 in the finger 62. This presser foot serves to press and support the opposite edge of the work while being acted upon by the first saw 31, see Figure 9. The work now advances and the strip which is being sawed 10 from the work is engaged and separated or sprung off from the work by the splitter finger 64. The first sawed surface on one side of the work is now engaged by the beveled roller 65 mounted in the adjustable arms 70 which rolls cooperate with the presser-foot 66 to hold the work down onto its support while the second saw 31 is operating on the opposite side of the work thus accurately controlling the depth of cut to be 15 taken by this second saw and as the work still further advances the member 67 splits or springs off the sawed portion from the strip while the presser-foot 68 engages the outer end of the work to continue to hold it in position on its support until it has entirely passed through the machine and 20 been operated upon by both the saws.

Each time after the work has been passed through the machine the blank portion 46 of 30 the gear 39 is presented to the rack 38 permitting the carriage to quickly return to its starting position under action of its weight 43, when the finished work is removed and replaced by fresh work ready to be passed 35 through the machine as above described.

When a shaft with a straight taper is desired to be produced, a work-support similar to that illustrated in Figure 4, is provided having a straight taper from end to 40 end that is its supporting edges converge and one end of the support is raised higher than the other, thereby producing work such as that illustrated in Figure 14 with a straight taper from one end to the other. 45 By providing converging supporting edges it will be seen that the work is always supported close to the line of cut thereby reducing the possibility of spring of the work to the minimum. Where work is produced 50 such as that illustrated in Figure 15 having such for instance as a reduced neck portion as at 69 and an enlarged end portion 73, a work-support having a supporting edge similar to that illustrated in Figure 7 must be 55 provided wherein a raised portion 71 on the support corresponds with the reduced portion 69 in the work and the reduced portion 72 in this support corresponds to the enlarged portion 73 in the work so that when this shape 60 of work is desired this style of support is employed and the work being of a flexible nature is pressed by the different presser members down onto the support and caused to follow the supporting contour thereof so 65 that after having been sawed or cut, when

sprung to normal will correspond to that of the contour of the support as illustrated in Figure 15, or the contour of the support may be in any desired form to produce work of any desired shape.

In order to absorb the shock of the rapidly returning carriage I have mounted a spring buffer or dash pot 74 which is engaged by the carriage as it approaches the outer end of its stroke to send it back to its starting position.

In some instances instead of employing saws set at an angle for cutting the wood, a pair of cutters 75 each having its teeth set at the desired angle to the plane of its 80 face or the plane of its rotation, may be employed such as that illustrated in Figure 18, or in still other cases a pair of such cutters 76 may be set together providing a single cutter having a V-shaped toothed 85 groove, may be employed such as that illustrated in Figure 19.

By the use of my improved sawing or cutting machine the edges of strips of materials may be very rapidly sawed with beveled 90 edges or it may be substantially V-shape in cross section if desired and the sawed strips may be assembled to form sectional shafts or members for any desired purpose.

By the use of my improved machine it 95 will be seen that the opposite sides of strips of bamboo may be accurately cut at the desired angle in cross section and also with the desired end-to-end taper and that without disturbing or removing the outer surface or shell of the wood which is extremely hard and tough and which it is very desirable to be preserved in order to obtain the maximum strength to the built-up shaft formed of it.

The foregoing description is directed solely towards the construction illustrated, but I desire it to be understood that I reserve the privilege of resorting to all the mechanical changes to which the device is susceptible, the invention being defined and limited only by the terms of the appended claims.

I claim.

1. A machine for cutting a strip of wood, comprising cutters arranged to operate on the opposite side edges of the strip to cut the same on converging angles, a longitudinally disposed extended strip support in the machine having a relatively longitudinal travel with respect to the cutters, and means for adjusting the ends of said support vertically to set it on an incline to the plane of said longitudinal travel, whereby the cutters are caused to cut the strip on an end-to-end taper as it passes through the machine.

2. A machine for cutting a strip of wood, comprising cutters arranged to operate on the opposite side edges of the strip to cut the same on converging angles, an extended support for the work having end-to-end

- converging strip-supporting edges, the cutters and support having a relative longitudinal travel and means for separately adjusting the opposite ends of said support vertically relative to the cutters to determine the inclination of said support to the plane of said travel by which an end-to-end taper of the strip may be produced by action of the cutters upon it.
- 10 3. In a machine for cutting strips of wood, a carriage, means for driving the same, a strip-support in said carriage having end-to-end converging strip supporting edges, cutters for operating on opposite side edges of the strip to cut the same on converging angles, and means for adjusting said support in said carriage relative to said cutters to control the depth of cut and also to produce an end-to-end taper of the strip by action of said cutters upon it.
- 15 4. In a machine for cutting strips of wood, inclined cutters arranged to operate on opposite sides of the work to cut the side edges thereof on a bevel, a longitudinally-movable carriage, a work-supporting member mounted on said carriage, and means for providing relative vertical adjustment of the ends of said support in said carriage whereby its height and inclination may be
- 20 regulated to determine the depth of the cut and its taper from end to end.
- 25 5. In a machine for cutting strips of wood, cutters to operate on oppositely-disposed vertically-inclined planes to cut the sides of the work to V-shape, a longitudinally-movable carriage, a work-support mounted on said carriage and having a vertical screw adjustment at its ends whereby the depth of the cuts and the end-to-end taper of the work may be regulated.
- 30 6. In a sawing machine having a pair of saws arranged to operate on oppositely-disposed vertically-inclined planes to cut the sides of the work to V-shape, a longitudinally-movable carriage, a longitudinally-disposed work-support on said carriage having a longitudinal concavity for a portion only of its work supporting surface, and presser means for depressing the work into said concavity.
- 35 7. In a machine for cutting strips of wood, a carriage, means for driving the same, a strip support in said carriage, cutters for operating upon opposite sides of the strip to cut its edges on converging angles, a work-support having a longitudinal depression in it for a portion only of the length of its work-supporting face, and a fixed guide member for depressing a portion of the work to follow the contour of said depression.
- 40 8. In a machine for cutting strips of wood, cutters to operate on oppositely-disposed vertically-inclined planes to cut the sides of the work to V-shape, a longitudinally-movable carriage, a work-support mounted on said carriage, the work-engaging portion of said support being provided with a longitudinal cavity for a portion only of its length, and means for bending the work to follow the contour of said work-support as it is presented to the cutters so as to produce a curved contour in the work.
- 45 9. In a machine for cutting strips of wood, cutters arranged to operate on oppositely-disposed vertically-inclined planes to cut the sides of the work to V-shape, a longitudinally-movable carriage, a work-support mounted on said carriage, the work-engaging section of said support being provided with a longitudinal concavity for a portion of its length, and a presser member fixed relative to the carriage for bending the work to follow the contour of its support while passing and being acted upon by the cutters to produce a curved contour in the work.
- 50 10. In a machine for cutting strips of wood, a cutter arranged to operate on oppositely-disposed vertically-inclined planes to cut the sides of the work to V-shape, a longitudinally-movable carriage, a vertically-adjustable work-support mounted on said carriage, and a relatively-fixed frame carrying one or more yieldably mounted downwardly pressing and laterally guiding and supporting members for retaining the work in proper position on its support while being acted upon by said cutter.
- 55 11. In a machine, for cutting a strip of wood, cutters arranged to operate on opposite sides of the work and vertically-inclined in opposite directions, a longitudinally-movable carriage having a longitudinally-disposed groove therein, a work-support adjustably mounted in said groove, screw-threaded adjustment for moving said support vertically in said groove, and means for locking said support in adjusted position.
- 60 65 70 75 80 85 90 95 100 105 110
- In testimony whereof I affix my signature.
HENRY K. B. DAVIS, JR.
